TABULATING MECHANISM FOR TYPE-WRITING MACHINES

Walter H. Boal, Chicago, Ill., assignor, by mesne assignments, to Underwood Elliott Fisher Company, New York, N. Y., a corporation of Delaware

Application December 26, 1931, Serial No. 583,303

21 Claims. (Cl. 197—178)

This invention relates to typewriting machines and more particularly to the tabulating mechanism thereof.

One object of the invention is to provide for locking the tabulator keys and for automatically releasing same when the tabulating movement of the carriage is completed.

Another object of the invention is to cushion the arrest of the carriage movement to prevent undue shock or jar.

A further object is to lighten the action of the tabulator keys, by causing the carriage, when advanced to a new position, to store power for the retraction of the tabulator blades.

15 A still further object is to provide tabulating mechanism, including a variable stop, acting to arrest the carriage without shock and coacting with means on the carriage to store power for the retraction of the tabulating mechanism and serving to cause the unlocking of the tabulator keys.

20 Another object is to provide a mechanism serving to cushion the carriage, unlock the tabulator keys and retract the tabulating mechanism.

Another object is to provide tabulator retracting springs which also serve as carriage cushioning springs.

25 To the accomplishment of these objects one embodiment of the invention resides in the construction and arrangement of parts hereinafter more fully described, illustrated in the accompanying drawings and defined in the appended claims.

30 In the accompanying drawings:

Figure 1 is a perspective view of a portion of an Elliott-Fisher typewriter equipped in accordance with my invention; the parts being shown in the position they occupy when a tabulator key is locked down and a tabulator blade is in interfering relation with the carriage cushioning device and the tabulator stop at the moment of key release;

35 Figure 2 is a vertical sectional view showing the carriage cushioning device and the unlocking bail;

Figure 3 is an enlarged detail perspective view showing the tabulator stop and parts mounted thereon;

40 Figure 4 is a vertical section through a portion of the typewriter showing a tabulator key unlocked and the retracting springs under tension;

45 Figure 5 is an enlarged detail perspective view of the unlocking bail, detached;

Figure 6 is a grouping of various stages of the tensioning of the retracting springs.

5 My invention relates to a tabulating mechanism and particularly to a tabulating mechanism for typewriters, for instance, the Elliott-Fisher typewriter of commerce. The general organization of the tabulating mechanism of these well-known machines is disclosed in Patent No. 1,280,697 to H. A. Foothorap.

10 Machines of the class described include a frame, of which only the tabulator bar 1, is shown, which supports a carriage 2, the casing 3, of which has a cover 4, upon which is mounted a series of tabulator keys 5. When a tabulator key 5, is depressed, connections which include a tabulator key lever 6, and a rod 7, connected thereto, cause a rock-shaft 8, to rock and thus swing one of a series of tabulator blades 9, by means of a link connection 10, into the plane of a variable stop 11. Since, as usual, the carriage 2, is released to travel at the time the tabulator key 5, is depressed, its movement will bring the tabulator blade 9, into engagement with the stop 11. Ordinarily, upon the release of the key, a retracting bail 12, swung from the blade shaft 13, retracts the blade under the impulse of springs 14, assisted by the key re-tarding springs 6a.

15 In accordance with my invention the tabulator key 5, when depressed is automatically locked by the engagement of its notched stem with the flange 15, of the locking bar 16, swung upon its bearings 17, by the springs 18, connected to the casing 3. The tabulator key remains locked until the tabulating movement of the carriage 20 has been completed.

To unlock the key, when the carriage has come to rest, I provide an unlocking bail 19, mounted upon the shaft 13, and including side arms 20, and 21, connected by rods 22, to which is secured a comparatively wide contact plate 23.

25 It will be particularly noted in Figure 1 that the retracting bail 12, has springs 14, connected to the forwardly extended portions 20a, and 21a, of the arms 20, and 21, respectively, 40 of the unlocking bail 19, because the present invention contemplates putting these springs under abnormal tension for reasons to be described later.

When coincidentally with the depression and locking of a tabulator key 5, a tabulator blade 9, is swung back into a path obstructed by the variable stop 11, the movement of the carriage to its next position is designed to operate a carriage cushioning device 24, mounted on the 55

stop 11. This cushioning device, when thus operated serves to operate the unlocking bail 19, and release the tabulator key through suitable connections comprising a rod 25, and a 5 slotted bracket 26, secured to the locking bar 16.

The carriage cushioning device 24, includes a contact slide 27, normally projecting beyond the left side of the stop 11, and connected to a spring-retained bell-crank lever 28, fulcrumed 10 on the stop 11, in a suitable housing. The bell-crank lever 28, has pivoted to one arm, the contact slide 27, as stated, and to the other arm is connected a bail operator 29. When the carriage is released in the usual manner and travels 15 to its new position, its arrest is cushioned by the engagement of the projected tabulator blade with the contact slide 27. As the slide yields, the bell-crank 28, is swung to shift the bail operator 29, forward, to engage the plate 23, and 20 operate the unlocking bail 19.

The described operation of the unlocking bail by the carriage, as it comes to rest, accomplishes important results. First, as its movement is resisted by the blade retracting springs, 25 it increases the tension of these springs which thus become part of the carriage cushioning mechanism. Second, it stores power in these springs for the retraction of the tabulator blades thus permitting the employment of comparatively 30 weak key retracting springs, and third, it unlocks the keys to permit the retraction of the tabulating mechanism as the carriage is finally arrested by the tabulator stop.

The unlocking bail 19, when swung, elongates 35 the springs 14, and thus increases their tension and when the key is unlocked, the springs, in which power has thus been stored, will swing the blade retracting bail 12, to retract the tabulator blade and assist the key retracting springs 40 to restore the operating connections to normal position. This happens when the springs have been tensioned and the arm 21, draws back the rod 25, which swings the locking bar 16, out of engagement with the notched stem of the 45 key 5, allowing the described retraction of the entire tabulating mechanism.

It will be noted in Figure 6 that the springs 14 at *a* are first elongated to the rear, as at *b*, by the action of the tabulator blade bearing 50 against the tabulator blade retracting-bail when the key is depressed. A second bail causes the springs to be elongated further in the opposite direction, as at *c*, when it is abnormally tensioned by said bail operating to unlock the key. 55 As at *d*, tension is released by the operation of the blade retracting bail returning the blade which is now possible with the unlocking of the key. Finally the springs resume their normal position, as at *e*.

By utilizing blade retracting springs in which 60 power is stored by the carriage, the burden of retraction placed on the key retracting springs is materially lessened. Therefore, I am enabled to use comparatively light key retracting springs which materially lightens the action of the tabulator keys.

A description of the operation of my invention is as follows:

When a tabulator key is depressed and locked, 70 the tabulator blade has been swung back into the plane of the carriage cushioning device and stop on the tabulator frame. The carriage travel when released brings the blade into engagement with the slide which yields and operates the bail operator to exert pressure on the 75

contact plate of the unlocking bail which is caused to swing. This tensions the blade retracting springs by the time the blade finally arrests the carriage, by contact with the fixed stop. The springs, under tension, perform a 5 dual function. They cushion the arrest of the carriage movement and operate the unlocking bail which through suitable connections releases the key from its locked condition. The tabulating mechanism, upon the unlocking of the key, 10 is retracted to normal position.

It is thought from the foregoing, the arrangement and operation of the illustrated construction will be clearly understood, but I reserve 15 the right to effect such structural modifications and variations as may come fairly within the scope of the protection prayed.

What I claim is:

1. The combination with a frame and carriage of a tabulating mechanism including stops, 20 a stop retracting bail, retracting springs connected to the bail, and a contact member movable on one of the stops and operated by the carriage and means for opposing the retracting springs to the movement of the contact member. 25

2. The combination with a frame and carriage of a tabulating mechanism, retracting springs therefor, and a contact member and a retracting bail cooperatively related to opposite 30 ends of the springs, said contact member being disposed for actuation by the carriage.

3. The combination with a frame and carriage of a tabulating mechanism including stops 35 on the frame and carriage, a stop retracting bail, a second bail, a contact member arranged to be moved by the carriage and to move the second bail, and a spring connected to both bails.

4. The combination with a frame and carriage of a tabulating mechanism including keys, and retracting springs, a key lock and means 40 yieldingly opposing the final movement of the carriage to prevent jar and operative to store power in the retracting springs and to operate 45 the key lock to unlock a key.

5. The combination with a frame and carriage of coacting tabulator stops, a movable contact member mounted on one stop and operated by the carriage, a bail operator actuated by the 50 contact member, a bail mounted on the carriage and operated by the bail operator and springs opposing the movement of the bail.

6. The combination with a frame and carriage of a tabulating mechanism including stops 55 on the frame and carriage, a stop retracting bail, a second bail, a contact member arranged to be moved by the carriage, a bail operator actuated thereby to move the second bail and a spring connected to both bails. 60

7. The combination with a frame and carriage, of a carriage stop, adjustable on the frame, a carriage cushioning device mounted on the stop and a stop mounted on the carriage to directly and successively engage the cushioning device 65 and carriage stop.

8. The combination with a frame and carriage, of a tabulator stop on the frame, a contact member movably mounted thereon, tabulator stops on the carriage, and a spring mounted on 70 the carriage and resisting the movement of said contact member on the frame.

9. The combination with a frame and carriage, of coacting tabulator stops, a contact member carried by a stop and movable thereon, a bail 75

- operated by the contact member and a spring opposing the movement of the bail.
10. The combination with a frame and carriage, of coacting tabulator stops, a movable contact member on one stop to cushion the arrest of the carriage, a bail mounted on the carriage and operated by the contact member and a spring opposing the movement of the bail to assist in the cushioning of the carriage.
- 10 11. The combination with a frame and carriage, of a tabulating mechanism including a stop movable into and out of its operative position, a retracting spring for said stop and means operated by the carriage to store power in said stop retracting spring.
12. The combination with a frame and carriage, of a tabulating mechanism including a stop movable into a plane obstructed by another stop, a spring for retracting the stop, and means including said stop retracting spring, for cushioning the arrest of the carriage.
13. The combination with a frame and carriage, of a tabulating mechanism, including stops, a stop retracting bail, operating springs for said bail and means for opposing said springs to the movement of the carriage.
14. In a typewriter the combination with a frame and carriage, of tabulating mechanism including keys, key locking mechanism, means operated by the carriage to operate the key locking mechanism for unlocking the keys and for storing power for their retraction.
15. In a typewriter the combination with a frame and carriage, of tabulating mechanism including keys and stops, key locking mechanism and means including a carriage-operated member mounted on a stop and movable relative to the stop to operate the key locking mechanism to unlock the keys.
- 40 16. The combination with a frame and carriage, of tabulating mechanism including coacting stops, unyielding in the direction of carriage travel, of carriage cushioning means including a spring and means whereby said spring will serve as a retracting spring for the tabulating mechanism.
17. The combination with a frame and carriage, of tabulating mechanism including coacting stops, a retracting spring for said mechanism and means operated by the carriage against the resistance of said spring to cushion the arrest of the carriage and to store power in the spring for the retraction of the tabulating mechanism.
18. The combination with a frame and carriage, of a tabulating mechanism including a co-acting stop on the frame, a contact member thereon and a carriage cushioning spring mounted on the carriage and opposing the movement of the contact member on the frame to cushion the final portion of the tabulating movement.
19. The combination with two relatively movable elements, to wit, a frame and carriage, a stop on one of said elements, a contact member movably mounted on the stop and a spring mounted on the other element and opposing movement of the contact member relative to the stop.
20. In a machine of the class described, tabulating mechanism including coacting stops and keys, key locking mechanism releasable to unlock a depressed key, and a device associated with one stop and movable relative thereto to unlock a key when engaged by another stop.
21. In a machine of the class described, tabulating mechanism including coacting stops and keys, a key lock movable to locked and unlocked position, a member mounted on a stop and yieldable relative thereto to operate the key lock to unlock a key when engaged by another stop and serving to cushion the arrest of the stop last named.

WALTER H. BOAL.
